UNITED STATES PATENT OFFICE.

MILFORD J. WILSON, OF PAINESVILLE, OHIO.

DESIGN FOR A METAL BINDING.

SPECIFICATION forming part of Design No. 18,620, dated September 18, 1888.

Application filed June 11, 1888. Serial No. 276,747. Term of patent 7 years.

To all whom it may concern:

Be it known that I, MILFORD J. WILSON, a citizen of the United States, residing at Painesville, in the county of Lake and State of Ohio, have invented and produced a new and original Design for Metal Binding and Corner-Pieces for Oil-Cloth and Carpets, of which the following is a specification, reference being had to the accompanying drawing, forming part thereof.

The drawing is a view of a section of the said newly-designed binding, which consists of two side pieces and a corner-piece. In use the binding would be connected with oil-cloth or carpets, ordinarily of a rectangular form—that is, the binding, which consists of the longitudinal and corner pieces, would be on the four sides of the oil-cloth and corners thereof.

The leading features of my design consist in raised or struck-up projections in an angular and curved relation to the right line of the binding, the general view of which presents the appearance of a twisted form or rope-like configuration running over the face of the strips and corners, as shown in the drawing.

In the drawing, A represents the central portion of the binding, which consists of curved

or twisted-like projections presenting the appearance of a rope form. Each side of this metal strip B has a bead upon the edges thereof, as indicated at C D.

The general contour of the design is intended to present to the eye a continuous rope-shaped configuration extending over the entire length of the binding, including the corners thereof.

The design of the corners E is essentially the same as side strips, which are connected to form a continuous design binding around the carpet of twisted strands or rope-like form. In the interior angles of the corners are formed radial projections F, radiating from the junction of the angle G to the line H, embracing the two lines of the angle, as shown in the drawing.

I claim and desire to secure by Letters Patent, viz:

The design for metal binding for oil-cloth, carpets, &c., substantially as herein described and shown.

In testimony whereof I affix my signature in presence of two witnesses.

MILFORD J. WILSON.

Witnesses:

W. H. BURRIDGE,
B. F. EBLER.
